UNITED STATES PATENT OFFICE.

WALTER L. CLARK, OF NEW YORK, N. Y.

PASTE-TUBE.

953,373.

Specification of Letters Patent. Patented Mar. 29, 1910.

Application filed January 17, 1907. Serial No. 352,697.

To all whom it may concern:

Be it known that I, WALTER L. CLARK, a citizen of the United States, and resident of New York, in the county and State of New York, have invented certain new and useful Improvements in Paste-Tubes, of which the following is a specification.

This invention relates to packages or receptacles for viscous or powdery materials, and more particularly to that type of receptacle which comprises a rigid tube having an outlet at one end and a piston contained within the tube and provided with means for forcing it forward to expel the material therefrom, my improvements being intended to provide a light, durable and practical receptacle of this sort which will be simple and inexpensive in construction and will also have certain other advantages hereinafter set forth.

In the accompanying drawings,—Figure 1 is a longitudinal section through a receptacle made in accordance with my invention, partially emptied of its contents; Fig. 2 is a cross section on the line 2—2 in Fig. 1; Fig. 3 is a plan view of the piston shown in Figs. 1 and 2, and Fig. 4 is a view in longitudinal section of a slightly modified form of piston.

The receptacle illustrated in the drawings consists of a rigid cylindrical tube 2 provided at one end with a central nozzle 3 or other suitable outlet, which nozzle may be externally screw-threaded to receive a removable cap 4 for closing the same when desired. That end of the tube 2 which carries the nozzle 3 is curved outwardly or forwardly somewhat, as shown at 5, and the piston, in the form shown at 6 in Figs. 1, 2 and 3, is stamped from sheet metal and has a short central neck or tubular portion 7, being also shaped to conform substantially to said end portion 5 of the tube 2, so that it will completely expel the contents of the tube when forced to the extreme front end 45 of the latter. The convex contour thus given to the piston greatly strengthens and stiffens the same, when made of sheet metal, so that it can be made of stock which is much thinner than would be required if the piston were flat, and which in practice is just thick enough to permit the neck 7 to have internal screw threads tapped in it. Said piston is originally located at the rear end of the tube 2, behind the material with 55 which the same is filled, and is forced forward as desired by means of a rod 8 which

extends longitudinally within the tube from one end to the other, or substantially so, and passes through the neck 7, being screw-threaded throughout the operative portion 60 of its length to fit the internal threads on said neck. At its rear end the rod 8 passes through the corresponding end of the tube 2, and is provided on the exterior of the latter with operating means such as a milled 65 head 9, this end of the tube being preferably closed by means of a concave sheet metal cap 10 set into the tube, as shown, so as to provide a space for the reception of the head 9 and thus protect the latter from liability 70 to injury as well as from being turned accidentally.

It will be seen that the location of the neck 7 with respect to the rest of the piston is such that the point of engagement of the rod 75 8 with said piston is somewhat in advance of the periphery of the latter, the result being that the greater portion of the piston is drawn rather than pushed forward, so that said piston has no tendency to become 80 cramped or slanted in the tube and hence does not require to be provided at its periphery with a broad guiding surface or the like for the purpose of preventing such cramping or slanting and the strains on the 85 rod 8 and the engaging screw threads which would be incident thereto. This feature contributes to the possibility of making the piston of thin sheet metal as above described without detriment to the durability and 90 capacity for practical operation of the device, as will be evident.

In the construction illustrated in full lines in Fig. 1 the threaded rod 8 has no bearing on the cap 10 to resist a rearward or outward 95 movement of said rod but is freely movable through said cap in either direction, and in this case the piston is not forced forward by turning the rod 8 but by screwing the latter backward through the piston and tube for a 100 suitable distance, according to the quantity of material which it is desired to force out of the tube, and then pushing said rod forward by a direct endwise pressure on the head 9, the piston being moved forward with 105 the rod by reason of the threaded engagement of said parts. This arrangement is useful not only because it simplifies the construction but also because it enables the user to determine with accuracy the amount of 110 material expelled or to be expelled at a given operation, since this amount will obviously

depend upon the distance through which the rod 8 is screwed backward through the piston in case said rod is then pushed forward to the limit of its movement. A receptacle embodying this feature of my invention is thus particularly adapted for use in situations where the amount of material expelled therefrom cannot be determined by inspection, as in case the receptacle is used 10 as a reservoir for a fountain brush, for example, and it will be evident that said feature may be embodied in receptacles which differ more or less in other respects from the specific construction above described. If preferred, however, the rod 8 may be provided with an abutment or bearing adapted to prevent its rearward movement through the cap 10, such as a collar 11 shown in dotted lines in Fig. 1, in which case the piston cannot be 15 moved in either direction except by rotating said rod. In this case some means for preventing rotation of the piston should be provided, and in Figs. 2 and 3 I have shown an arrangement for this purpose according 20 to which the tube 2 is made of a sheet of metal bent into cylindrical form and having its meeting edges interlocked to form a seam 25 12, which seam projects into and extends longitudinally within the interior of the tube 30 and serves as a guiding rib, the piston being provided with a notch 13 adapted to receive this rib and to slide along the same, and being thus prevented from rotating. The exterior of the tube is thus left smooth and 35 free from projections, while the expense of forming a special or additional guiding rib is avoided. In case the rod 8 is adapted to move longitudinally through the rear end of the tube no such rib will ordinarily be necessary, as the frictional resistance to the rotation of the piston will be sufficient to permit the rod 8 to be screwed backward through it, but said rib may nevertheless be retained as an incident to the manufacture of the tube 2 40 in the manner described.

The form of piston shown in Fig. 4 is so constructed as to make a practically fluid-tight fit with the interior of the receptacle, being particularly designed for use in cases 50 where the receptacle is to contain a material which is so soft or nearly fluid that it would be liable to leak out through the cap 10 around the rod 8 if allowed to get behind the piston. This form of piston comprises a thin flat disk 14 of cork or similar material clamped against the rear face of a body portion 15 by means of a thin disk 16 secured to the part 15 by pins 17 or the like, said disk 14 being of a size to make a close fit with the interior of the receptacle. The body portion 15, which may conveniently be made of wood, conforms in contour on its front side to the front end portion 5 of the receptacle, and it and the disk 16 are of slightly less 60 diameter than the cork disk 14 so as to per-

mit the latter to conform with accuracy to the interior of the receptacle. The internal threads for engagement with the rod 8 may be formed on either or both of the parts 15 and 16, and the operation of this form of piston is the same as that of the piston 6, except that the cork disk provides a tight packing between the body portion of the piston of which it forms a part and the receptacle in which it moves.

I claim as my invention:

1. A receptacle of the character described, comprising a tube having an outlet at one end, a piston adapted to slide longitudinally in said tube, and a rod provided with an externally screw-threaded portion passing through the piston, in threaded engagement therewith, and adapted to extend beyond said piston in both directions, said rod being movable in an endwise direction through one 85 end of the tube, without rotation.

2. A receptacle of the character described, comprising a tube having an outwardly-projecting front end provided with a central outlet, a piston conforming substantially in 90 contour to said front end of the tube and having a central perforation provided with internal screw-threads, and a rod provided with an externally screw-threaded portion passing through the threaded perforation in 95 the piston and adapted to extend beyond the latter in both directions, said rod being movable in an endwise direction through the rear end of the tube, without rotation.

3. A receptacle of the character described, comprising a tube having an outwardly-projecting front end provided with an outlet and closed at its rear end by a set-in cap to provide a recess as described, a piston conforming substantially in contour to the front 105 end of the tube and having a central perforation provided with internal screw threads, and a rod provided with an externally screw-threaded portion passing through the threaded perforation in the piston and 110 adapted to extend beyond the latter in both directions, said rod being movable in an endwise direction through the rear end of the tube, without rotation, and being provided on the exterior of the tube with operating means.

4. A receptacle of the character described, comprising a cylindrical tube made of sheet metal and formed with an internally-projecting longitudinal seam, said tube having 120 an outwardly-projecting front end provided with an outlet and being closed at its rear end by a set-in cap to provide a recess as described, a notched piston conforming substantially in contour to the front end of the tube and having a central perforation provided with internal screw-threads, and a rod provided with an externally screw-threaded portion passing through the threaded perforation in the piston and adapted to ex- 125 130

tend beyond the latter in both directions, said rod being movable through the cap in an endwise direction, without rotation, and being provided on the exterior of the tube 5 with operating means.

5. A receptacle of the character described, comprising a tube having an outwardly-projecting end provided with an outlet, a sheet-metal piston conforming substantially 10 in contour to the outlet end of said tube and having a central, forwardly-extending neck

which is internally screw threaded, and a threaded rod passing through the neck of said piston in operative engagement therewith and through one end of the tube. 15

In testimony whereof, I have hereunto subscribed my name this 3d day of January 1907.
